UNITED STATES PATENT OFFICE.

PETER H. MEYER, OF BUFFALO, NEW YORK.

DESIGN FOR A COMBINED PAPER-WEIGHT AND MAGNIFYING-GLASS.

55,632.

Specification for Design.

Patented July 6, 1920.

Application filed January 22, 1920. Serial No. 353,339. Term of patent 14 years.

To all whom it may concern:

Be it known that I, PETER H. MEYER, a citizen of the United States, residing at Buffalo, in the county of Erie and State of New York, have invented a new, original, and ornamental Design for a Combined Paper-Weight and Magnifying-Glass, of which the following is a specification, reference being had to the accompanying drawing, forming a part thereof.

In the accompanying drawings:

Figure 1 is a side elevation of the com-

bined paper weight and magnifying glass embodying the design.

Fig. 2 is a perspective view thereof.

I claim

The ornamental design for a combined paper weight and magnifying glass, as shown.

PETER H. MEYER.
